UNITED STATES PATENT OFFICE.

EMORY CROUSE, OF WICHITA, KANSAS.

LIQUID-DISPENSING APPARATUS.

Application filed March 3, 1925. Serial No. 12,823.

This invention relates to liquid dispensing systems and has reference more particularly to improvements in apparatus for use in dispensing gasoline.

5 In dispensing gasoline, it is customary to first pump the gasoline into an elevated glass container graduated in gallons. From this elevated container the gasoline is run by gravity into the fuel tanks of the automobiles.

In Patent No. 1,466,273, granted to me on August 28, 1923, I have described and claimed a liquid dispensing apparatus that is adapted for use where the gasoline is transferred from the underground storage tank into the glass dispensing container, by means of a pump, as distinguished from that type of installation where the gasoline is transferred by means of air under pressure. In installations of this type it is often desirable to locate the storage tank at some distance from the dispensing apparatus which makes it desirable that only a single pipe shall be needed to connect the tank with the dispenser. In the patent, above identified, I have shown an apparatus in which only a single pipe is used to connect the storage tank with the condenser.

It is the object of this invention to modify the construction shown and described in my above referred to patent so as to simplify the same and so as to make it possible to place the overflow or float tank underground, instead of within the casing of the dispensing apparatus. This makes it possible to drain the dispensing container into the float tank at night and in other ways simplifies the construction.

The above and other objects which will appear as the description proceeds, are attained by means of a construction and arrangement that I will now proceed to describe in detail, reference for this purpose being had to the accompanying drawing in which my invention is illustrated and in which the single figure shows a vertical section through a liquid dispensing apparatus constructed in accordance with my present invention.

50 In the drawing numeral 1 designates a transparent glass container that is graduated in gallons and fractions thereof. This bowl is clamped between the base member 2 and top 3 by means of a central rod or bar 4. The dispensing bowl assembly rests upon the top of the conical casing 5. A suction or

fill line 6 extends from the base bracket 7 upwardly and into the dispensing container where it terminates at a point near the top of the latter. A hand or power operated pump 8 is interposed in the fill line in the manner shown. An overflow pipe 9 extends parallel with the fill pipe 11 from the bracket 7 to a point near the top of the dispensing container where it terminates a short distance below the upper end of the fill pipe. A drain pipe 10 connects the strainer 11 with the delivery or dispensing hose 12. A valve 13 serves to control the escape of the liquid through the pipe 10. A by-pass indicated as a whole by numeral 14 connects the drain pipe 10 with the overflow pipe 9. This by-pass is controlled by a stop-cock 15 which may be opened at night or whenever it becomes necessary or desirable to drain the container 1. Unless some special construction, such as that described in the above identified patent is resorted to, it becomes necessary to extend the overflow pipe 9 to the storage tank 16 which frequently increases the cost of the material and the labor charge for the installation. In my present invention, I have provided an auxiliary tank 17 whose capacity may be small when compared to the capacity of the tank 16, but which must be slightly larger than the container 1 so that it will be possible to drain the latter at any time. The suction or fill line 6, in the preferred construction, extends through the tank 17, in the manner shown, and passes from thence to the inside of the storage tank 16 near the bottom of which it terminates in a foot valve 18. Within the tank 17 is a float operated valve having a body portion 19 which is provided with an opening which is controlled by a movable valve member 20 that is connected to the float controlled lever 21 by means of a link 22. When the tank 17 is empty the valve is closed but when liquid enters the tank 17 in sufficient quantity to raise the float 23, the valve member 20 is moved to open position, in a manner perfectly obvious from an inspection of the drawing. The overflow pipe 9 enters the tank 17 in the manner shown.

It is now evident that any overflow that may occur while filling the container 1, as well as the contents of the latter when the stop-cock 15 is opened, will flow into the tank 17. I have shown the tank 17 provided with a vent pipe 17^a that extends upwardly and opens into the top of the measuring bowl.

- This permits the air to escape from the tank to the bowl when the latter is drained. The storage tank 16 is filled through the pipe 24 and is vented through pipe 25. In order 5 that the pump 8 may be primed, if this should become necessary, I have attached to the pipe 6, at a point directly above the pump, a priming pipe 26 controlled by a valve 27.
- 10 Let us now assume that the parts are assembled in the manner shown and that the pump is operated. Gasoline will be transferred from the storage tank to the graduated container 1. When the level of the 15 gasoline in the container 1 reaches the top of the overflow pipe 9, it will overflow through this pipe and pass into the tank 17. As soon as this occurs the pump should be stopped. No harm, however, will be done if the pumping 20 is continued for as soon as the float 23 opens the valve, the pump, instead of raising gasoline from the storage tank, will merely return the gasoline from the overflow tank to the container 1. This circulation may be 25 continued as long as desired. At night or at any other time, when it is necessary or advisable to drain the container 1, the stop-cock 15 may be opened. This permits the gasoline to pass down and into the tank 17 30 where it will remain owing to the fact that the foot valve 18 prevents it from returning to the storage tank 16. The float 23 will, however, open valve 19 and when the pump is operated the liquid in tank 17 will 35 be the first to be returned to the container. As soon as the valve 19 closes, liquid will be raised from the storage tank. I have shown the fill line 6 as passing through the tank 17, but this is not absolutely essential, although desirable for structural reasons. It 40 is evident, however, that the pipe 6 may merely have a branch extending into the tank 17 and controlled by a valve like the one described.
- 45 The main point of distinction between my prior invention, above referred to, and this one is that in this construction the overflow pipe opens directly into the tank 17 and the latter is large enough to permit the entire

contents of the container 1 to be drained into 50 it. This makes it possible to use a foot valve in the lower end of the fill pipe which cannot be done where the float tank is smaller than the container 1. With my present construction the tank 17 may be placed 55 underground which minimizes the fire risk. In the patent above referred to, there is no foot valve corresponding to the valve 18 as this would prevent the overflow from returning to the storage tank. The tank 17 60 is shown broken away and has any capacity at least slightly greater in volume than the transparent container 1.

Having now described my invention, what I claim as new is:

An apparatus for dispensing liquid in measured quantities, comprising, in combination, a storage tank adapted to be placed under ground, a measuring bowl adapted to be supported in elevated position above the 70 storage tank, a suction pipe connecting the storage tank and the measuring bowl, a pump in said suction pipe, for transferring liquid from the storage tank to the measuring bowl, an overflow pipe extending downwardly from a point within the measuring bowl, an overflow tank between the measuring bowl and the storage tank, the lower end of the overflow pipe being in communication with the interior of the overflow 75 tank, said suction pipe having an opening in communication with the interior of the overflow tank, a float controlled valve for opening and closing said communicating opening and a check valve in the suction 80 pipe between the overflow tank and the storage tank, said overflow tank having a capacity at least as great as the maximum capacity of the measuring bowl, whereby the 85 entire contents of the latter may be transferred to the overflow tank and a vent pipe connected at its lower end with the overflow tank and having its upper end opening at a point above the maximum liquid level of 90 the measuring bowl.

In testimony whereof I affix my signature.

EMORY CROUSE.
